(57) **CLAIM**

The ornamental design for a sliding nozzle plate, as shown and described.

DESCRIPTION

FIG. 1 is a front view of a sliding nozzle plate of the present invention.

FIG. 2 is a rear view of the sliding nozzle plate of FIG. 1.

FIG. 3 is a top plan view of the sliding nozzle plate of FIG. 1.

FIG. 4 is a bottom plan view of the sliding nozzle plate of FIG. 1.

FIG. 5 is a right side view of the sliding nozzle plate of FIG. 1.

FIG. 6 is a left side view of the sliding nozzle plate of FIG. 1.

FIG. 7 is a perspective view of the sliding nozzle plate of FIG. 1.

FIG. 8 is a sectional view of the portion in the direction indicated by the arrows of plane 8-8 of the sliding nozzle plate of FIG. 4; and,

FIG. 9 is an enlarged partial view of the portion indicated by the arrows 9-9 of the sliding nozzle plate of FIG. 4.

The features shown in broken lines depict environmental subject matter only and form no part of the claimed design.

1 Claim, 9 Drawing Sheets
